UNITED STATES PATENT OFFICE.

CHARLES M. BENTLEY AND EDWIN W. HARGISSL, OF HERMITAGE, MISSOURI.

DESIGN FOR A TRACE-CARRIER.

47,779.

Specification for Design.

Patented Sept. 7, 1915.

Application filed March 3, 1915. Serial No. 11,872. Term of patent 14 years.

To all whom it may concern:

Be it known that we, CHARLES M. BENTLEY and EDWIN W. HARGISSL, citizens of the United States, residing at Hermitage, in the county of Hickory and State of Missouri, have invented a new, original, and ornamental Design for Trace-Carriers, of which the following is a specification, reference being had to the accompanying drawing, forming a part thereof, in which the figure is a perspective view of a trace-carrier showing our new design.

We claim:

The ornamental design for a trace carrier as shown.

In testimony whereof we affix our signatures in the presence of two witnesses.

CHARLES M. BENTLEY.
EDWIN W. HARGISSL.
